United States Patent Office.

ROBERT MACDONALD, OF NEW YORK, N. Y.

Design No. 3,247, dated November 17, 1868.

DESIGN FOR LADIES' COLLARS AND CUFFS.

The Schedule referred to in these Letters Patent and making part of the same.

To all whom it may concern:

Be it known that I, ROBERT MACDONALD, of the city, county, and State of New York, have invented a new and original Design for Ladies' Collars and Cuffs; and I do hereby declare that the following is a full, clear, and exact description thereof, which will enable others skilled in the art to make and use the same, reference being had to the accompanying drawings forming a part of this specification.

Figure 1 represents a plan view of my improved design for ladies' collars.

Figure 2 is a plan view of a collar-design as heretofore made.

Similar letters of reference indicate corresponding parts.

This invention relates to a new design for ladies' and children's collars and cuffs, and consists in printing the stripes or lines thereon in such manner that the whole system of such stripes or lines will form a uniform and ornamental design.

Heretofore the stripes were always printed or otherwise affixed in parallel rows upon the faces of the col-

lars or cuffs, (as in fig. 2,) and did never, owing to the peculiar form of the cuffs or collars, form a uniform pattern at the ends of such collars or cuffs.

To avoid this I print, paint, or affix in any other suitable manner, upon the faces of the collars or cuffs, stripes or lines *a a* which radiate all from one common centre, as shown in fig. 1, said centre being either the same, or in line with that from which the upper and lower edges of the collar are described.

The lines are either plain lines, or are ornamented in suitable manner.

I do not confine myself to any particular form of them, my invention consisting solely in the application of the radial lines or stripes, as set forth.

Having thus described my invention,
I claim as new, and desire to secure by Letters Patent—

The design for collars and cuffs herein described.

ROBERT MACDONALD.
